DESIGN FOR A CASING FOR AN OZONIZER

Hans V. Hjermstad and Philmore F. Sperry, Chicago, Ill., assignors to Federal Electric Company, Chicago, Ill., a corporation of New York

Application March 15, 1938, Serial No. 75,838

Term of patent 14 years

To all whom it may concern:

Be it known that we, Hans V. Hjermstad and Philmore F. Sperry, citizens of the United States, residing in Chicago, in the county of Cook and State of Illinois, have invented a new, original, and ornamental Design for a Casing for an Ozonizer, of which the following is a specification, reference being had to the accompanying drawing forming part thereof.

The figure is a perspective view of the casing for an ozonizer, showing our new design.

We claim:

The ornamental design for a casing for an ozonizer, as shown.

HANS V. HJERMSTAD.
PHILMORE F. SPERRY.
